UNITED STATES PATENT OFFICE.

CLAUDIUS DORNIER, OF FRIEDRICHSHAFEN, GERMANY, ASSIGNOR, BY MESNE ASSIGNMENTS, TO HIMSELF AND DORNIER METALLBAUTEN GESELLSCHAFT MIT BESCHRÄNKTER HAFTUNG.

FLYING-MACHINE PROPULSION.

Application filed March 31, 1921. Serial No. 457,542.

To all whom it may concern:

Be it known that I, CLAUDIO DORNIER, a citizen of the German Empire, residing at Friedrichshafen, Germany, have invented 5 certain new and useful Improvements in Flying-Machine Propulsion, of which the following is a specification.

My invention relates to flying machines and its particular object is to render flying 10 machines capable of varying their speed within wide limits. Ever since the beginning of high speed flying, one of the objects aimed at has been to increase the difference between the maximum and the minimum flying 15 speed. The only means which has hitherto been found practicable, and which consisted in increasing the size of the supporting planes while at the same time lessening the objectionable resistance, however, 20 only solved the problem within very narrow limits, whereas, on the other hand, the helicopters, which had been proposed in great numbers, and which promised a more satisfactory solution of the problem involved, all 25 failed on account of insurmountable difficulties of construction.

It is with due regard to these facts that my invention will be found to cover a form of flying machine construction, which may 30 be readily realized practically and which allows of the speed of flight to be varied within wide limits, and this by means of a flying machine the traction propeller of which is firmly lodged, together with the respective motor, in the customary manner in 35 the forward section of the hull, while the lateral propelling sets are pivoted to the machine in such a manner that the driving shafts may be translated from the horizontal position 40 into a position in which the pressure propellers will operate after the manner of lifting propellers. It will further prove of special advantage to so dispose their pivot, that the weights of the said propelling sets 45 will be either entirely, or at least partially balanced relatively to their pivots. It will be found that for purpose of securing the aforesaid balancing use may also be made with much advantage of the receptacles of 50 fuel, oil or other running material, and that

by suitably positioning them within the machine.

Generally speaking, the propelling sets will be rotated about their points only into two positions, i. e., a horizontal for high 55 speeds, and a vertical one for low speeds. However, by suitable means the said propelling sets may also be rotated into intermediate positions.

In the drawings affixed to this specification and forming part thereof a flying machine embodying my invention is illustrated 60 by way of example. In the drawing—

Fig. 1 is a side elevation

Fig. 2 a plan view, and

Fig. 3 a front elevation of a monoplane, in which the lateral motor sets are adapted to be rotated, separately, about a horizontal axis.

Referring to the drawing, the stationary 70 motor 1 (Fig. 1), disposed in the forward end of the flying machine serves to drive a traction propeller 2. The side motors 3 are lodged to rotate, together with their respective propellers 4 about a pivot 5. If high 75 speed be required, then the propellers 4 operate, with the driving shaft in horizontal position, as pressure propellers. If now the speed is to be reduced, then the motors 3 and propellers 4 are rotated into the positions 3' 80 and 4', respectively, in the direction indicated by the arrow 6, so that the propellers 4' will now come to act as lifting propellers.

The invention is mainly intended for monoplanes with self supporting wings 85 requiring no special staying means, since it is in connection with this particular form of construction that the advantages peculiar to my invention may be fully utilized. However, there is no fundamental objection to applying my invention also to other forms of flying machines, and in the same way, the invention may be successfully realized in the case of flying machine having more than 90 three motors.

I claim:

In an aeroplane in combination, a hull and a supporting plane connected with said hull, a stationary motor on said hull and a traction propeller operatively connected with 10

said motor and disposed in front of said supporting plane, a motor pivotally suspended on either side of said hull, immediately below said supporting plane and adapted to rock through an angle of 90° about a horizontal axis extending transversely to said hull and a pressure propeller operatively associated to each rockable motor in such a way as to press the air rearwards, whenever its shaft extends horizontally, or downwards, when its shaft is directed vertically. 10

In testimony whereof I affix my signature.

CLAUDIUS DORNIER.
